UNITED STATES PATENT OFFICE.

ROBERT K. CLARK, OF WEST SPRINGFIELD, MASSACHUSETTS, ASSIGNOR TO THE AMERICAN THREAD COMPANY, OF JERSEY CITY, NEW JERSEY, A CORPORATION OF NEW JERSEY.

APPARATUS FOR TREATING YARN.

1,253,999.

Specification of Letters Patent. Patented Jan. 15, 1918.

Application filed April 4, 1917. Serial No. 159,655.

To all whom it may concern:

Be it known that I, ROBERT K. CLARK, a citizen of the United States, residing at West Springfield, county of Hampden, State 5 of Massachusetts, have invented certain new and useful Improvements in Apparatus for Treating Yarn, of which the following is a full, clear, and exact description.

My invention relates to the manufacture of 10 cotton yarn and has for its object to provide apparatus for producing a cotton yarn having a twisted core with a flocculent exterior adhering thereto capable of being used in the production of thick and fluffy fabrics, 15 sweaters and the like, of a warm and soft nature, in which the interstices of the fabric when loosely knit or woven shall be largely filled up with a flocculent material adhering to the surface of the yarn. Cotton yarn of 20 such nature may be described as "fluffed 25 yarn", and the action by which it is produced may be called "fluffing" by which I mean the partial combing out of enough of the fibers of a strand of yarn to produce a continuous flocculent surface thereon, which is secured thereto. I believe such fluffed yarn, as well as the apparatus and 30 method which I have devised for producing it, to be novel with me.

35 The following is a description of my invention, reference being had to the accompanying drawings, which show apparatus embodying the mechanical features of my invention and suitable for carrying out my process and also show the product produced thereby. In these drawings,

Figure 1 shows a side elevation of a machine embodying my improved apparatus;

Fig. 2 is a longitudinal section of the 40 same;

Fig. 3 is a plan view;

Fig. 4 is a diagrammatic view of the apparatus, and

Fig. 5 is a view of the product.

45 Referring more particularly to the drawings, 1 is a frame carrying a creel 2 supporting a series of bobbins 3, having wound thereon loosely twisted yarn 4. This loosely twisted yarn is made up of a plurality of loosely 50 twisted strands which are themselves loosely twisted together, the yarn preferably being a two-ply yarn. Mounted upon the frame is a guide tension bar 5, beneath which the

strands 4 of yarn pass to a grooved guide-bar 6, from which they pass to other guide 55 bars 7 and 8, the latter being also grooved, and to leather covered nip or pulling rollers 9 and 10 between which they pass. The nip rolls are power-driven by gearing from the shaft of an adjacent roller 12 reducing from 60 about 5 to 1. The tension bar 5 alines the various strands so that they thereafter lie in a common plane and creates enough tension to prevent irregularities of pull of the 65 yarn coming off the spools being transmitted to the rest of the machine. The guide-bars 6, 7 and 8 are shown in the form of rolls, which may be mounted so as to freely revolve. Between the bars 6 and 7 is a roller 11 covered with projecting needles of springy 70 tempered wire so as to have a fluffing or napping surface and between the bars 7 and 8 is a second similar fluffing roller 12, the two rollers being geared together, by gears 13 and the shaft of one of them is 75 provided with a pulley 14 which is driven by a belt from the motor 15. The wire teeth or needles of these fluffing or napping rollers are preferably straight instead of bent as in ordinary card clothing and are substantially perpendicular to the surfaces of their rollers. The fluffing rollers are substantially the same as in regular gigging 80 machines for finishing woven fabrics, except that I preferably make the needles 85 straight. The roller 11, as shown in Fig. 2, operates clockwise, while the other roller 12 operates counter-clockwise, so that their movements are in opposite directions, the first roller turning toward the point from 90 which the yarn passes and its movement thus being against or in opposition to the movement of the yarn. The bars 6, 7 and 8 are vertically adjustable and are so adjusted 95 that the strands of yarn passing over them are in proper engagement with the needle points upon the fluffing rollers 11 and 12 to raise the fiber on the yarn exterior. The bar 7 positions the strands for the two rollers 11 and 12 and acts to prevent the yarn 100 from getting slack and entangled in the needles. The amount of flocculent material formed on the exterior of the yarn can be varied somewhat by changing the positions of the strands relatively to the needles by adjusting the bars 6, 7 and 8. The fluffing

rollers 11 and 12 revolve at a relatively high rate of speed so that their peripheral surfaces move at about the rate of 1,000 feet a minute, while the yarn passes forward at the 5 rate of about 75 feet a minute, due to the corresponding peripheral speed of the nip rolls 9 and 10. The teeth upon the fluffing rollers engaging fibers upon the exterior of the strands partially free them from the 10 twisted strands with the result that there is produced upon the surface of the strands a flocculent exterior composed of a multiplicity of fibers, one end of each of which extends into the twisted core, so as to be intermingled 15 with the fibers thereof, resulting in a product which is represented, as well as it can be, in Fig. 5. Each strand after this flocculent exterior has been produced thereon passes between the nip rollers 9 and 10 20 and is then wound into cylinders or other suitable form by any suitable take-up mechanism 16, preferably a drum winder having a suitable traverse. The strands of yarn as they pass from the bar 6 are kept under a 25 light tension so as to prevent the strands from being caught upon the fluffing rollers. The action of the fluffing roller 11 increases this tension in the strands of yarn that have passed it, but should not stretch 30 them so tightly as to interfere with the fluffing needles getting hold of fibers on their exteriors and partially freeing the same from the twisted cores. The machine treats a multiplicity of strands at the same time, 35 the strands being kept parallel and treated independently as they pass between the bars 6 and 8.

In carrying out my process I supply a plurality of separate strands of loosely 40 twisted multiple-ply yarn to the machine in the manner above described and subject the strands as they pass between the points on the bars 6 and 8 under the tension as above specified, to the fluffing action of rollers 11 and 12 so as to partially comb out and free 45 enough of the fibers extending to the exterior of the untreated yarn to produce the desired flocculent result. I preferably cause the roller 11 first engaging the yarn to rotate in the direction of the point from 50 which the yarn comes, *i. e.*, in opposition to the movement of the yarn, and the other roller 12 to rotate in the opposite direction. This results in a counter-balancing pull on 55 the intervening portion of the yarn so that the pull necessary to draw the yarn through the machine is not seriously affected by the action of the fluffing rollers and a slack which may become entangled is not likely to 60 be produced. This relation of peripheral rotation also accomplishes the result of raising the fibers in more than one direction, thus producing a more general fluffing. As the 65 yarn passes between the two points 6 and 8, it revolves slightly on its own axis on ac-

count of the twist therein and the tension under which it is placed, and also on account of the action of the fluffing cylinders thereon, with the result that substantially all sides of the strands are subjected to the 70 fluffing or napping action of the wire needles so that the flocculent surface extends to all sides of the strand.

The yarn after being treated so as to constitute my new product, is composed of a 75 loosely twisted core 17 having a fluffy or flocculent surface 18 comprising a multiplicity of fibers which have ends extending into the strands of said twisted core and free ends presenting a woolly external surface. 80 The outer ends of these partially released fibers are free while the inner ends extend into the twisted core so as to be intermingled with the fibers of the strands of which it is composed and secure the flocculent exterior to the core. With cotton treated by this process, the length of the exposed ends of the fibers constituting said flocculent surface may on the average exceed twice the diameter of the core when the core does not 85 exceed one sixteenth of an inch, as shown in Fig. 5.

While I am aware that woven fabrics have been teazled by machinery, and a teazled product produced thereby, I am not 95 aware that anyone has devised an apparatus for or process of teazeling unfabricated lengths of yarn, or produced a length of yarn having a continuous teazled surface consisting of fibers which were originally 100 within a twisted strand, but have been pulled out so as to be, as in my product, partially but not wholly detached.

The process and product described herein are claimed in a divisional application filed 105 by me on the 21st day of June, 1917, Serial No. 175,983.

As will be evident to those skilled in the art, my invention permits of various modifications without departing from the spirit 110 thereof or the scope of the appended claims.

What I claim is:

1. In an apparatus for treating yarn, the combination of a package holder for a wound strand of yarn, means for continuously passing an extended length of said yarn held under tension between two points, a fluffing surface engaging said yarn as it passes between said points, and means for moving said fluffing surface toward one of 115 said two points so as to partially free fibers extending to the surface of said yarn, and a take-up for an individual strand of yarn.

2. In an apparatus for treating yarn, the combination of a package holder for a 125 wound strand of yarn, means for continuously passing an extended length of said yarn between two points, a fluffing surface engaging said yarn as it passes between said points, means for moving said fluffing sur- 130

face continuously toward the point from which said yarn comes so as to partially free fibers extending to the surface of said yarn, and a take-up for an individual strand of yarn.

5. 3. In an apparatus for treating yarn, the combination of a package holder for a wound strand of yarn, means for continuously passing an extended length of said 10 yarn between two points, two fluffing rollers engaging said yarn as it passes between said two points, means for rotating said fluffing rollers in opposite directions so as to partially free fibers extending to the surface of 15 said yarn, and a take-up for an individual strand of yarn.

4. In an apparatus for treating yarn, the combination of a package holder for a wound strand of yarn, means for continuously 20 passing an extended length of said yarn between two points, two fluffing rollers engaging said yarn as it passes between said two points, means for rotating the first of 25 said fluffing rollers in opposition to the movement of said yarn, and the other roller in the opposite direction so as to partially free fibers extending to the surface of said

yarn, and a take-up for an individual strand of yarn.

5. In an apparatus for treating yarn, the 30 combination of means for supporting a plurality of packages of wound yarn to be treated, means for holding a plurality of extended lengths of said yarn parallel and moving them between two points, a fluffing 35 roller engaging said strands as they move between said two points, means for rotating said fluffing roller, and take-ups for the individual strands of yarn.

6. In an apparatus for treating yarn, the 40 combination of means for supporting a plurality of packages of wound yarn to be treated, means for holding a plurality of extended lengths of said yarn parallel and moving them between two points, two fluffing 45 rollers engaging said strands as they pass between said two points, means for rotating said fluffing rollers, supporting means engaging said strands at points between said fluffing rollers and holding said 50 strands away from the axis of said rollers, and take-ups for the individual strands of yarn.

ROBERT K. CLARK.
